Primary Examiner — Michelle E. Wilson*Assistant Examiner* — Richard E Yenchesky*(74) Attorney, Agent, or Firm* — Harness, Dickey & Pierce, P.L.C.(57) **CLAIM**

The ornamental design for an abrading, buffing, and finishing spherocylinder, as shown and described.

DESCRIPTION

Pat. application Ser. No. 16/173,227, filed on Oct. 29, 2018, the same day as this application, entitled "Buffing Spherocylindrical made of Compressed Material" is hereby incorporated by reference.

FIG. 1 is a side elevation view of the abrading, buffing, and finishing spherocylinder incorporating my new design;

FIG. 2 is a front elevation view thereof;

FIG. 3 is a top plan view thereof; and,

FIG. 4 is a rear elevation view thereof.

The broken line portions of the drawing disclosure are for illustrative purposes only and form no part of the claimed design.
